UNITED STATES PATENT OFFICE.

EDWIN R. STORM, OF NEW YORK, N. Y.

GOVERNOR FOR ENGINES.

1,115,984.

Specification of Letters Patent.

Patented Nov. 3, 1914.

Application filed December 8, 1911. Serial No. 664,637.

To all whom it may concern:

Be it known that I, EDWIN R. STORM, a citizen of the United States, residing at New York, in the county of New York and State of New York, have invented a new and useful Governor for Engines, of which the following is a specification.

My invention relates to improvements in engines operated by a fluid; and the objects of my improvement are, first, to provide a governor that will control the number of revolutions of the engine; second, to provide a means for varying the number of revolutions of the engine at the will of the operator; third, to provide a governor that will proportion the intake to the amount of work required of the engine; fourth, to provide a governor that when applied to explosion engines will permit of a very low velocity or a minimum number of revolutions when the engine is not in use, and a velocity as much higher when the engine is in use as the operator desires; fifth, to provide a governor that when applied to explosion engines will when the engine is running beyond any predetermined speed permit the passage of cool air through the cylinder instead of pulsing the hot exhaust back-and-forth; sixth, to provide a governor that when applied to explosion engines will mix the air and carbureting fluid more thoroughly than is done in the present practice; seventh, to provide a governor that when applied to an explosion engine installed in an automobile will in a measure supersede change-speed gears and give the operator greater control of his car. I attain these objects by the mechanism illustrated in the accompanying drawings in which:—

Figure 1 is an elevation of the governor applied to an explosion engine installed in an automobile. Fig. 2 is a section through the governor showing the valve, plate, frame, rods, spring and lever controlling the tension of the spring. Fig. 3 is an end-view showing the casing, the front guide for the stem, frame, rod, spring and lever controlling the tension of the spring. Fig. 4 is a cross-section taken on the line A—B, indicated in Fig. 2, showing the openings in the casing, the plate, and the openings in the plate. Fig. 5 is an elevation of the rear guide for the valve and plate stem, showing the openings,

between the arms, which permit the free passage of the fluid. Fig. 6 is an enlarged sectional view of the stem showing the raceways for the ball bearings. Fig. 7 is a front elevation of the valve showing it as a simple disk. Fig. 8 is a front elevation of the fulcrumed rod showing the fork on one end. Fig. 9 is a sectional view showing a form of joint for holding an end of the frame and fulcruming the rod. Fig. 10 is an end elevation of the sleeve which works on the fulcrumed rod, showing the lug for attaching the spring, also, the trunnions for the slippers. Fig. 11 is a sectional view of one of the slippers showing the hole for the reception of the trunnion. Fig. 12 is an elevation of one of the slippers showing the hole for the reception of a trunnion.

Similar reference numerals refer to similar parts throughout the several views.

The casing 1, formed of any convenient size and shape is shown in the preferred form and is formed with the threaded end 2, the guide 3, the chamber 4, the neck 5, the chamber 6, the threaded end 7, the lugs 8, and the lugs 9. See Figs. 1, 2, 3 and 4.

The threaded end 2, is formed to receive the nipple 10. The nipple 10 also screws into the threaded end 11 of the carbureter 12, which may be of any form and make. See Figs. 1 and 2.

The guide 3 is, in the preferred form, shown as formed integrally with the casing 1, and consists of a tube 13 supported by arms 14. See Figs. 2 and 3.

The chamber 4 is formed to permit the fluid to pass freely around the valve 15. See Fig. 2.

The neck 5 is formed with the passage 16 which is of approximately the same size and shape as the valve 15, so as to permit the valve to move into and close the passage. See Fig. 2.

The chamber 6 is formed with a cross sectional area considerably greater than the cross sectional area of the passage 16 and when applied to explosion engines is pierced by the openings 17. See Figs. 1, 2, 3 and 4.

The threaded end 7 is formed to receive the reducer 18. The bottom of the threaded end 7 is formed with the recess 19 to receive the guide 20. The guide 20 is held in place by the reducer 18. See Fig. 2.

The lugs 8 are formed to receive one end of the frame 21, and are pierced with the

holes 22 for the holding-bolt 23. See Figs. 1, 2 and 3. The lugs 9 are formed to receive an end of the frame 21 and are pierced with the holes 24 which receive the holding-bolt 25. See Figs. 1 and 2. The holding-bolt 23 is held in place by the washer 26, the nut 27, and the cotter 28. See Figs. 1 and 3. The holding-bolt 25 is held in place by the washer 29, the nut 30 and the cotter 31. See

10 Figs. 1 and 3.

The guide 20, fitted to the recess 19, is formed with the tube 32, supported by the arms 33. The tube 32 is formed with the cylindrical hole 34, and the tube 13 with the cylindrical hole 35. See Figs. 2, 3, 5 and 6. To the holes 34 and 35 is fitted the stem 36. See Fig. 2. The stem 36 is formed with the shoulders 37 and 38 and with the raceways 39. See Figs. 2 and 6.

20 On the stem 36 are placed the valve 15 and the plate 40. The valve 15 is held against the shoulder 37 by the nut 41, and the plate 40 is held against the shoulder 38 by the nut 42. See Fig. 2. The plate 40 is formed with 25 a cylindrical rim 43, of any desired length, which is fitted to the chamber 6. The plate is perforated by a number of openings 44 whose aggregate area will approximate as nearly as desired the area of the valve 15. See Figs. 2 and 4.

To the raceways 39 are fitted the balls 45, which roll on the surfaces of the holes 34 and 35 and carry the stem 36 together with the valve 15 and plate 40 mounted thereon.

30 See Figs. 2 and 6.

The reducer 18 fitted to the threaded end 7 is formed of a length to give proper clearance between the end of the tube 32 and the connection 46. The connection 46 may be a 40 nipple fitted to the threaded hole 47, or it may be the inlet pipe or the manifold pipe. See Figs. 1 and 2.

To the holding-bolt 25 is fitted the hole 48 of the lever 49. See Fig. 2. The lever 49 is 45 formed with arms 50 and 51. See Figs. 1 and 2. The arm 50 is formed with parallel

ways or guides 52 for the slippers 53, and these guides are connected by the head 54 which is perforated by the hole 55. See 50 Figs. 1, 2 and 3. The slippers 53 are formed to fit partly over and slide on the parallel ways 52, and are provided with the holes 56. The parallel ways may be of any section desired. See Figs. 2, 3, 11 and 12. To the 55 holes 56 are fitted the trunnions 57 of the sleeve 58. The sleeve 58 is perforated by the longitudinal hole 59, and is formed with the lug 60. The lug 60 is pierced by the hole 61. See Figs. 1, 2 and 10. In the hole 61 is secured one end of the retractile helical spring 62 whose other end is secured in the hole 55.

60 See Figs. 1, 2 and 3. To the hole 59 is fitted the rod 63 which is formed with the eye 64 and the fork 65. See Figs. 2 and 8.

65 The eye 64 is pierced by the hole 66 to

which is fitted the sleeve 67. The sleeve 67 is fitted to the holding bolt 68 and between the ends of the frame 21. To the sleeve 67 are fitted the thimbles 69 which are formed of a length to properly fill the space between the 70 ends of the frame 21 and the rod 63. See Fig. 9. The holding-bolt 68 is secured in place by the washer 70, the nut 71, and the cotter 72. See Figs. 1, 3 and 9.

The fork 65 is formed to pass through 75 and work in the opening 73, which is shown communicating with one of the openings 17. The fork is shown with the ends of the tines resting against the shoulder 37. The fork 65 is normally held against the front of the 80 opening 73, which acts as a stop, by the elasticity of the retractile spring 62. See Figs. 2 and 3.

The arm 51 formed at any convenient angle to the arm 50 is provided with an eye 85 74, or fork, as required, to receive the end 75 of the rod 76. In the eye, or fork, 74, is formed the hole to which is fitted the bolt 77. The bolt 77 is held to place by the washer 78, the nut 79 and the cotter 80. 90 See Figs. 1, 2 and 3.

To the bolt 77 is fitted the hole in the end 75 of the rod 76. The rod 76 is made of convenient shape and length to reach from the arm 51 to the lever 81 to which it is 95 properly jointed at 81'. The lever 81 fulcrumed at 82 may be of the well known type of controlling levers mounted in a sector frame 83 provided with notches 84 in which fit the end of the locking-bolt 85. The 100 locking-bolt 85 is controlled by the rod 86 and lever 87. See Figs. 1 and 2.

While the drawings indicate threaded ends, 2 and 7, it is not to be understood that this is to be the fixed form, as in some types 105 of engines, or in larger units, other forms of joining may be required, as, for instance, flanges, gaskets, and bolts, necessitating a corresponding change in the form of the ends 2 and 7.

110 The operation of the mechanism when applied to an explosion engine is as follows: The engine being in motion draws in air through the inlet pipes and discharges it through the exhaust pipe. This current of 115 air passing through the carbureter takes up the vapor of the hydro-carbon and so passes into the cylinder where it is exploded, thus accelerating the motion of the engine and also increasing the velocity of the air 120 passing through the inlet pipes. This air passing through the carbureter 12, the nipple 10, and the spaces between the arms 14 of the guide 3, impinges against the valve 15. By reason of the enlarged chamber 4, 125 the carbonized air passes over the edge of the valve 15 and through the passage 16, impinging against the plate 40, passes through the openings 44, into the rear of the chamber 6. From chamber 6 it passes 130

through the spaces between the arms 33 of the guide 20, through the reducer 18 into the inlet pipe 46 and so to the cylinder or cylinders 88. See Figs. 1 and 2. The air, 5 impinging against the valve 15 and plate 40 tends to move the valve end plate in the direction of the flow of air, when moved a sufficient distance in this direction the valve 15 moves up to and closes the passage 16. As 10 the inertia of the engine causes it to continue to rotate, a partial vacuum is formed in the inlet pipe 46, the reducer 18 and the chamber 6. The partial vacuum causes the air in the carbureter to press against the valve 15 moving it still farther into the passage 16, carrying with it the stem 36, the plate 40 and the fork 65 and lengthening the retractile spring 62.

The plate 40 may be so spaced with regard 20 to the valve 15, that when the valve 15 just enters the passage 16 the cylindrical rim 43 is about to uncover the openings 17. Then when the valve 15 moves into the passage 16 the rim 43 will uncover the openings 17 25 allowing uncarbonized air to flow through the openings into the chamber 6, impinging against the plate 40, as it passes through the openings 44, and tending to move the plate in the direction of the flow of air. Passing 30 through the openings 44 in the plate 40 into the rear of the chamber 6, it continues through the openings between the arms 33 of the guide 20, through the reducer 18 and the inlet pipe or pipes 46 to the cylinder 35 or cylinders 88. As the air is uncarbonized it will pass through the cylinder without exploding and, consequently, there will be the retardation due to compression, friction and whatever work the engine may be doing. 40 This will overcome the inertia of rotation, which in turn will diminish the flow of air through the inlet pipes, lessen the impact of the incoming air against the plate 40 and permit the retractile spring 62 to return 45 the fork 65 to its normal position. The fork 65 having the ends of the tines bearing against the shoulder 37 will move the shoulder 37, the stem 36, the valve 15, and the plate 40 to their normal positions. This will 50 bring the cylindrical rim 43 forward, closing the openings 17 and carry the valve 15 out of the passage 16, allowing the carbonized air to flow through the carbureter 12, the nipple 10, the openings in the guide 3, the 55 chamber 4, impinging against the valve 15, flowing around the valve 15, through the passage 16, into the chamber 6, impinging against the plate 40, passing through the openings 44, through the remainder of the 60 chamber 6, through the openings in the guide 20, through the reducer 18, and through the inlet pipe or pipes 46, to the cylinder or cylinders 88, where it is compressed and exploded, accelerating the rotation of the 65 engine, and so repeating the operation. The

sleeve 58 sliding freely on the rod 63 and held in place by the trunnions 57 working in the holes 56 formed in the slippers 53, fitted to the sliding-ways 52, will be moved toward the fork 65 when the arm 50 is 70 moved toward the fork 65, and will be moved toward the eye 64 when the arm 50 is moved toward the eye 64. Because the fulcrum 25 of the lever 49 is at a distance from the fulcrum 68 of the rod 63, the distance from the center of the trunnions 57 to the center of the fulcrum 25 will vary as the arm 50 is moved toward the fork 65 or toward the eye 64. And, consequently, the slippers 53 will be moved toward the fulcrum 25 when the arm 50 is moved toward the fork 65, and the slippers 53 will be moved toward the head 54 when the arm 50 is moved toward the eye 64. The moving of the slippers 53 toward the fulcrum 25 increases the tension of the retractile spring 62, while the moving of the slippers 53 toward the head 54 diminishes the tension of the retractile spring 62. Also, the placing of the fulcrum 25 toward the fork 65 permits the greatest tension of the retractile spring 62 to be delivered with almost its full force to the shoulder 37 when the arm 50 is moved to its nearest position to the fork 65, and decreases the force of the spring on the shoulder 37 when the arm 50 is moved toward the fulcrum 68, both by reason of the diminished tension of the retractile spring 62 and the leverage of the rod 63 from the ends of the tines of the fork 65 to the fulcrum 68, over the distance from center of trunnion 57 to fulcrum 68. The lever 49, being connected by means of the arm 51, the rod 76, and the proper joints, to the lever 81; may be moved so as to bring the arm 50 toward the fork 65 or toward the eye 64, by moving the lever 81 in the proper direction thus increasing or diminishing the tension of the spring 62, and, consequently the resistance of the valve 15 and plate 40 to being moved from their normal positions. Hence, by properly moving the lever 81, the resistance of the valve 15 and plate 40 may be so altered that they will be moved from their normal positions whenever the rotation of the engine, or engines, having the cylinder or cylinders 88, exceeds the desired velocity. The lever 81 having the notched sector 83 and bolt 85 can be set to any desired position and so hold the rotation of the engine at any predetermined velocity.

As the velocity of the engine may be changed at the will of the operator, the necessity for speed gears, especially for mobile machines, as, for instance, automobiles, will be greatly lessened, or may be entirely 11 done away with, placing the machine under more perfect control of the operator than can be accomplished by stepped gearing.

It will be seen from the above description that when an engine exceeds the desired 11

velocity it will pump cool air through the cylinder, thus cooling its walls and relieving the radiators.

As the governor is intended to be applied to all forms of engines and vary according to their use and make, it is impossible to show in one drawing all the variations the governor with its frame, levers and rods would have to undergo to fit each engine, 5 it is, therefore, understood that I do not intend to confine myself to the form shown but to adapt it to the various makes of engines, and that I do not intend to confine myself to joining the lever to the stem by having the fork 65 bear against the shoulder 37, as in the various adaptations it may be found more expedient to connect the lever 63 in front of the valve 15, at the forward end of the stem, or, to have it bear against 33 the rear end of the stem; viz., the end to the left of the plate 40.

It will also be seen that it is immaterial whether the chambers 4 and 6 are formed integrally or are separated, or, whether the valve 15 and plate 40 are mounted on the same stem or on separate stems properly connected; or, whether plate 40, or its equivalent, is placed in and operated by the exhaust instead of the intake, so long as the valve 15 and plate 40 are operated by the passage of a fluid whose velocity is controlled by the engine.

It will also be seen that where an engine is desired to be run at a given velocity the controlling spring may be made to operate the valve and plate without the medium of the frame and levers.

It will also be seen that it is not necessary that the plate fit the chamber in which it works, nor that it be perforated, for, the area of the holes may be provided at the periphery of the plate in any manner desired.

Having described my invention, I claim 45 and desire to secure by Letters Patent—

1. In a governor, the combination of a casing having a passage; a valve; a movable perforated plate adapted to operate the valve to close the passage; a rod connecting the plate and the valve; a spring operatively connected with the valve; a manually operated rod adapted to control the tension of the spring; and means operatively connecting the rod with the spring.

2. In a governor, the combination of a casing having an inlet and an outlet and provided with chambers connected by a passage; a valve working within the casing; a plate working within a chamber and adapted to operate the valve to close the passage and having an area appreciably less than the cross-sectional area of the chamber; a rod connecting the plate and the valve; a spring operatively connected with the valve and acting thereon to open the

passage; a manually operated rod adapted to control the tension of the spring; and means operatively connecting the rod with the spring.

3. In a governor, the combination of a 70 chambered casing adapted to confine and conduct the fluid to be controlled; a valve within a chamber adapted to control the passage of the said fluid through the casing; a plate having an area appreciably less than 75 the cross-sectional area of a second chamber and movable within said second chamber, adapted to operate the said valve to restrict the flow of the said fluid; a rod connecting the plate and the valve; a lever operatively connected to the valve; a spring adapted to operate the lever to remove the said restriction; a manually operated rod; and means operatively connecting the rod with the spring.

4. In a governor, the combination of a chambered casing having an inlet to one chamber and an outlet to another chamber and a passage connecting the chambers; a valve working within one chamber adapted 90 to move into and close the passage; a perforated plate movably mounted in another chamber; a rod connecting the plate and valve; a lever operatively connected to the valve; a second lever; a spring connecting 95 the levers; and a manually operated rod connected to the second lever and adapted to control the tension of the spring.

5. In a governor, the combination of a chambered casing having a passage; a valve within the casing adapted to move into and close the passage; a stem on which the valve is mounted; a plate mounted on the said stem and adapted to operate the valve to close the passage; guides for the stem; an 105 adjustable spring adapted to operate the valve to open the passage; a normally operated rod adapted to control the tension of the spring; and means operatively connecting the rod with the spring.

6. In a governor, the combination of a casing having chambers and a passage connecting the chambers; guides in the casing; a stem working in the guides; a valve mounted on the stem; a perforated plate 115 mounted on the said stem and adapted to operate the valve to close the passage; a spring operatively connected with the valve and acting thereon to open the passage; a manually operated rod adapted to control 120 the tension of the spring; and means operatively connecting the rod with the spring.

7. In a governor, the combination of a chambered casing having a passage connecting the chambers; a valve in one chamber adapted to close the passage; a perforated plate working in another chamber; an operative connection between the plate and the valve; a lever bearing against the valve; and a spring adjustably engaging with the lever 125 130

and acting thereon to operate the valve so as to open the passage.

8. In a governor for fluid engines, the combination of a casing provided with ends adapted to operatively connect the governor with the engine and having chambers connected by a passage; guides in the casing; a stem working in the guides; a valve mounted on the stem and adapted to close the passage; a plate mounted on the stem and adapted to operate the valve to close the passage; a lever operatively connected with the stem and adapted to move and be moved by, the said valve and plate; and a spring 15 engaging with the lever and acting thereon to operate the valve so as to open the passage.

9. In a governor for fluid engines, the combination of an inlet pipe; a casing provided with ends adapted to be joined to the inlet pipe and having chambers connected by a passage; guides in the casing; a stem working in the guides; a perforated plate mounted on the stem and working in one of the 25 chambers; a valve mounted on the stem and adapted to close the passage; and a spring operatively connected with the stem and acting thereon to move the valve so as to open the passage.

30 10. In a governor for fluid engines, the combination of a chambered casing provided with an inlet passage and inlet holes; guides in the casing; a stem working within the guides; a valve mounted on the stem; a perforated plate mounted on the stem; a rim on the plate adapted to close the said inlet holes; and a spring operatively connected with the stem and acting thereon to move the valve and plate so as to open the inlet 40 passage and close the inlet holes.

11. In a governor, a casing provided with an end adapted to be joined to a pipe and with a recessed end adapted to be joined to an end-piece, and formed with a constricted 45 portion having a passage between the said ends; a guide fitted to the recess; arms formed in the guide; a tube supported by the arms formed in the guide; an end-piece adapted to be joined to the said recessed end 50 and provided with an end adapted to be joined to a pipe; arms formed in the casing; a tube supported by the arms formed in the casing; a rod working within the tubes; and a valve mounted on the rod adapted to move 55 into and close the passage.

12. In a governor, the combination of a casing having a passage; a valve adapted to close the passage; a plate adapted to operate the valve to close the passage; a frame joined to the casing; a lever fulcrumed in the frame and operatively connected with the valve; and a spring engaging with the lever and acting thereon to move the valve and open the passage.

60 13. In a governor, the combination of a

controlling valve; a frame; a lever fulcrumed therein; a manual operating rod connected to the said lever and adapted to move and hold the said lever in any desired position; a second lever fulcrumed in the 70 said frame and adapted to control the valve; and a spring connecting both levers.

14. In a governor, the combination of a controlling valve; a plate adapted to close the valve; a frame; a lever fulcrumed therein and adapted to open the valve; a sleeve working on the lever; a spring connected to the sleeve; a second lever fulcrumed in the 75 said frame operatively connected to the spring and adapted to alter the tension of the said 80 spring; a sliding member working on the second lever; a connection between the sleeve and sliding member; and a manual operating-rod connected to the second lever and adapted to move and hold the said second 85 lever in any desired position.

15. In a governor, the combination of a controlling valve; a frame; a lever fulcrumed therein; a manual operating rod connected to the said lever; sliding members 90 working on the said lever; a second lever fulcrumed in the said frame and adapted to control the valve; a sleeve slidably working on the second lever; a connection between the sleeve and sliding members; and a 95 spring connected to the sleeve and the manually operated lever.

16. In a governor, the combination of a controlling valve, a frame; a lever fulcrumed therein; sliding members working on the 100 said lever and provided with trunnion holes; a second lever fulcrumed in the said frame and adapted to control the valve; a sleeve slidably working on the second lever; trunnions on the sleeve fitted to the said trunnion holes; and a spring connecting the 105 sleeve and the lever provided with the sliding members.

17. In a governor, the combination of a controlling valve; a frame; a manually operated lever fulcrumed therein; sliding members working on the said lever and provided with trunnion holes; a second lever fulcrumed in the said frame and adapted to control the valve; a sleeve slidably working 110 on the second lever; trunnions on the sleeve fitted to the said trunnion holes; a perforated lug on the sleeve; an adjusting spring having one end joined to the lug and the other to the manually operated lever; and 115 means for holding the said manually operated lever in any desired position.

18. In a governor, the combination of a controlling valve; a frame; a manually operated lever fulcrumed therein and formed with portions adapted to act as sliding ways; sliding members working on the said portions adapted to act as sliding ways, and provided with trunnion holes; a second 125 lever fulcrumed in the said frame and adapt- 130

ed to control the valve; a sleeve slidably working on the second lever; trunnions on the sleeve fitted to the said trunnion holes; a perforated lug on the sleeve; a spring 5 joined to the lug and the manually operated lever; a notched frame; a latch-bolt adapted to hold the manually operated lever in any predetermined position and means connecting the manually operated lever with the 10 latch-bolt.

19. In a governor, the combination of a chambered casing having a passage; a valve in the casing adapted to close the passage; a plate adapted to operate the valve to close 15 the passage; perforated lugs on the casing; a frame adapted to be joined to the lugs; a lever fulcrumed in the frame and operatively connected with the valve; a spring engaging with the lever and acting thereon 20 to move the valve to open the passage; and a second lever fulcrumed in the frame and connected to the said spring and adapted to alter the tension of the spring.

20. In a governor, the combination of a locking frame; a hand lever; a latch-bolt thereon; a casing carrying a frame; a second lever fulcrumed in the frame; a rod joining the hand lever and the second lever; a third lever fulcrumed in the frame; a spring joining 25 the second and third levers; a valve in the casing; a plate connected to the valve; and an operative connection between the valve and the said third lever.

21. In a governor, the combination of a locking frame; a hand lever fulcrumed 35 therein; a latch-bolt on the said hand lever; a casing carrying a frame; a second lever fulcrumed in the frame; a rod joining the hand lever and the second lever; a third lever fulcrumed in the frame; a spring joining 40 the second and third levers; guides in the casing; a stem working in the guides; a valve mounted on the stem; a plate mounted on the stem; and an operative connection between the valve and the said third lever.

22. In a governor, the combination of a locking frame; a hand lever fulcrumed therein; a latch-bolt on the said hand lever; a chambered casing; a frame attached there- 50 to; a second lever fulcrumed in the frame; a rod joining the hand lever and the second lever; a third lever fulcrumed in the frame; a sliding member on the third lever; a con- 55 nection between the said sliding members; a spring engaging with the second lever and the said sliding member; guides in the cas- ing; a stem working in the guides; a valve mounted on the stem; a plate mounted on the stem; and shoulders on the stem adapted 60 to bear against the ends of the said third lever.

23. In a governor, the combination of a locking frame; a hand lever fulcrumed therein; a latch-bolt on the said hand lever; 65 a chambered casing having a passage connecting the chambers; a frame attached to the casing; a second lever fulcrumed in the frame; a rod joining the hand lever and the second lever; a third lever fulcrumed in the frame; a sliding member on the second lever; a sliding member on the third lever; a connection between the said sliding members; a spring engaging with the second lever and the said sliding members; guides 75 in the casing; a stem provided with raceways and fitted to the guides; balls in the raceways; a valve mounted on the stem; a plate mounted on the stem; and shoulders on the stem adapted to receive the ends of 80 the said third lever.

24. In a governor, the combination of a locking frame; a hand lever fulcrumed therein; a latch-bolt on the said hand lever; a chambered casing provided with an inlet 85 passage and inlet holes; a frame attached to the casing; a second lever fulcrumed in the frame; a rod joining the hand lever and the second lever; a third lever fulcrumed in the frame; a jointed member slidably 90 mounted on both the second and third levers; guides in the casing; a stem provided with raceways and fitted to the guides; balls in the raceways; a valve mounted on the stem; a plate mounted on the stem and having 95 portions removed; a rim on the plate adapted to close the inlet holes; shoulders on the stem; formed ends on the third lever adapted to bear against one of the said shoulders; and a spring engaging with the 100 second lever and the said jointed member and adjustably acting to move the valve and plate so as to open the inlet passage and close the inlet holes.

25. In a governor for fluid engines, a cas- 105 ing connected to the inlet pipe of the engine and provided with chambers and a passage joining the chambers; guides in the casing; a stem working in the guides; a valve mounted on the stem and adapted to be 110 moved by the operating fluid and restrict the passage; a plate mounted on the stem adapted to assist the operating fluid in moving the valve; a lever operatively connected with the stem; a spring engaging with the 115 lever and acting thereon to operate the valve so as to resist the restriction of the passage; and a manually operated rod adapted to control the tension of the spring.

EDWIN R. STORM.
